UNITED STATES PATENT OFFICE.

JOHN ALEXANDER COWAN, OF CALGARY, CANADA.

HARVESTER-BINDER.

SPECIFICATION forming part of Letters Patent No. 708,320, dated September 2, 1902.

Application filed October 10, 1900. Renewed July 30, 1902. Serial No. 117,710. (No model.)

To all whom it may concern:

Be it known that I, JOHN ALEXANDER COWAN, agent, of the city of Calgary, North-West Territories, Canada, have invented certain new and useful Improvements in Harvester-Binders, of which the following is a specification.

The object of my invention is to devise a harvester-binder in which the grain is elevated to a minimum height during the process of forming and binding the sheaves, pertaining more especially to that class of harvester-binders having an open rim or ground-wheel having a truck running on a track formed on its inner periphery and a harvester-frame pivoted at one end of the truck and vertically adjustable upon its other end.

It consists of the novel combinations, arrangement, and adaptation of parts, as more fully hereinafter described and claimed.

Figure 1 is an end elevation of my improved harvester-binder. Fig. 2 is a front sectional elevation of the same through the line *x y*, Fig. 1. Fig. 3 is a perspective view showing the means for retaining the grain on the elevator side of the binder during the process of binding. Fig. 4 is a perspective detail showing one form of adjustable connection between the rear portions of the harvester frame and truck. Fig. 5 is a skeleton view showing the method of adjusting the height of the harvester binder-frame.

In the drawings like letters of reference indicate corresponding parts in the different figures.

A is the frame of the binder, suitably shaped to support the different parts. *B* and *C* are arms extending laterally therefrom. The outer ends of these arms are turned downwardly and have a longitudinal bar *D* secured thereto immediately opposite a similar bar *E*, connected to the frame *A*.

F is a truck comprising the frame *G*, the main wheel *H*, and the guide-wheels *I*. The frame *G* is so proportioned that the guide-wheels *I* are located on or near an imaginary line forming the diameter of the open rim or ground wheel *J*. This open rim has a triangular track *K* formed on its inner periphery, with which the wheels *H* and *I* are suitably shaped to engage. Upon the forward end of the frame *G* at *a* is journaled the arm *B*.

The arm *C* is adjustably connected with the rear of the frame *G* at *b*. One form of adjustable connection is shown in Fig. 4. A 55 segmental rack *L* is rigidly connected to the arm *C*. This rack forms the arc of a circle struck from the center of the journal *a* and is adapted to slide through a guide-frame *M*, secured to the frame *G*. *N* is a pinion fast 60 on a spindle *c*, journaled upon the frame *G*. Upon the one end of this spindle is journaled a lever *O*, which is provided with a pawl *f*, adapted to engage the ratchet-wheel *d*, fast upon the spindle. *e* is a pawl pivoted upon 65 the frame and also adapted to engage this ratchet-wheel. It is evident that by reciprocating the lever is the pinion *N* may be caused to elevate the rack *L* to any desired extent, in which position it is securely held 70 by means of the pawl *e*. When the rear portions of the frame of the truck and the harvester are so separated and as the tongue of the binder tends to maintain it in a substantially horizontal position, it is evident that 75 the elevation of the binder above the ground may be increased as desired. (See Fig. 5.) Although the frame may be slightly tilted, yet the end of the tongue being practically a fixed point when the frame is raised it swings 80 from this fixed point; but as the end of the tongue is a suitable distance ahead of the body of the machine the angle of the frame relatively to the ground varies very little. It will be noticed that as the binder is raised 85 the truck assumes an inclined position from the rear forwardly and upwardly.

P is the table of the binder, *Q* the elevator, and *R* the binder-deck, which extends through or partially through the open rim *J*, the apex 90 between the elevator and binder-deck being substantially within the open rim. The elevator is much lower than in an ordinary binder and the binder-deck shorter, thus materially reducing weight and decreasing the 95 amount of handling required during the collection of a sheaf and the binding of the same. The conveyer may be provided with the usual conveying-canvas; but I prefer to use the carrying-chains shown in Fig. 2. 100

S represents the carrying-chains upon the binder-table, which pass around suitable sprocket-wheels, as shown. Similar chains *T* are provided on the elevator, passing around

the sprocket-wheels *j* upon the shaft *g* at the upper end of the elevator and around the sprocket-wheels *h* upon the shaft *i*, upon which shaft are also fixed the sprocket-wheels, 5 around which pass the chains *S*. From a sprocket-wheel *k* on one end of the shaft *g* extends a sprocket-chain to a sprocket-wheel *l*, fast on one end of a shaft *U*, suitably journaled upon the bar *D*. The other end of this 10 shaft *U* is provided with a crank-disk *m*, from which may be driven the cutter-bar. (Not shown.) Upon the shaft *U* is fast a bevel-pinion *n*, which meshes with a bevel gear-wheel *o*, fast upon the cross-shaft *p*, journaled upon the bars *D* and *E*. Upon this shaft 15 is fast a sprocket-wheel *q*, which is driven by a sprocket-chain from the sprocket-wheel *r*, revolving with the main wheel *H*. From this construction it is evident that the proper motion 20 will be given to the carrying-chains *S* and *T* while the machine is in motion.

V is an apron, preferably of sheet metal, supported above the elevator *Q*, so as to hold the grain in contact therewith. As this apron 25 is fast only at its lower side to the frame *s*, it accommodates itself readily to the quantity of grain passing up the elevator. To adjust its pressure equally from butt to head of the grain, it is preferably vertically divided, as 30 indicated at *t t*, so that different portions of it may spring independently of the rest. This apron does not extend to the top of the elevator, but is turned abruptly substantially at right angles to its general direction to form 35 the outwardly-turned upper end *u*. This end has slots *v* formed therein, in which play the fingers *A'*, which are connected to the rock-shaft *B'*, journaled in the frame *s*. When these fingers are in the position shown in Fig. 40 2, they form an extension of the apron *V* and maintain the grain in contact with the elevator till it is deposited upon the binder-deck.

As the binder-deck is short and the needle *C'* passes through it close to the apex, it is 45 necessary to provide means for retaining the grain at the elevator side of the binder during the binding of a sheaf. In order to accomplish this, I provide a series of rods *D'*, which may be extended upwardly through 50 holes at the apex of the binder-deck, as shown in Fig. 3. At the same time that these are extended the rock-shaft *B'* is operated to swing the fingers *A'* into the position shown in Fig. 3. The grain raised by the elevator is then 55 held between the upper end of the apron *V*, the fingers *A'*, and the rods *D'*. To operate the rods *D'*, as described, any suitable means may be provided. In Figs. 1 and 2 I show a shaft *E'* journaled upon the frame of the 60 binder and provided with a series of crank-arms *a'*, to which the rods *D'* are pivoted. One end of this shaft is provided with a short crank-arm *b'*, pivotally connected by a suitable connecting-rod with a longer crank-arm 65 *c'*, fast on the end of the rock-shaft *B'*. The parts are so proportioned that when the shaft *E'* is rotated to raise the rods *D'* the fingers *A'*

are swung back to the desired extent. Means must be provided for rocking the shaft *E'* when the needle rises in the operation of binding. It may be driven from any part, moving only during the binding of the grain. In Fig. 2 I show a chain and sprocket-wheel connection with the shaft *F'* of the needle, the chain being carried around suitable idlers, 75 as may be necessary. I do not show any specific means for driving the needle-shaft, nor do I show the knitter, as these form no part of my invention.

In order to assist the grain in moving onto the lower part of the elevator, I journal a shaft *G'* within the lower end of the apron *V* and provide it with a series of disks having fingers *d'* extending therefrom. These fingers extend through slots in the apron adjacent to the chains *S*.

The shaft *G'* is preferably driven by gearing from the shaft *i* and at the rear end, as seen in full lines in Fig. 1 and by dotted lines in Fig. 2. *H'* is a cover preferably connected 90 to the frame *s* and extending over the apex of the binder to shield the grain from the influence of wind.

From the above description it will be seen that I have devised a binder which will operate with a minimum amount of elevation of the grain, that I have devised simple means for increasing or decreasing the height of the binder from the ground, and that I have provided simple and effective means for retaining the grain upon the elevator side of the binder during the process of binding a sheaf.

What I claim as my invention is—

1. In a harvester-binder an open rim having a track formed on its inner periphery in combination with a truck running on the said track; and a harvester-frame journaled at one end of the frame of the said truck and adjustably supported upon it at the other end, substantially as and for the purpose specified.

2. In a harvester-binder an open rim having a track formed on its periphery, in combination with a truck having three wheels running on the track; a sprocket-wheel connected with the main wheel of the truck; a harvester-frame journaled at one end of the frame of the said truck and adjustably supported upon it at the other end; a cross-shaft journaled on the said harvester-frame; a sprocket-wheel on the shaft connected by a sprocket-chain with the sprocket-wheel on the main wheel of the truck; a shaft longitudinally journaled on the harvester-frame and geared to the aforesaid shaft; and a crank-disk on the forward end of the longitudinal shaft, substantially as and for the purpose specified.

3. In a harvester-binder, an open rim having a track formed on its inner periphery, in combination with a truck having three wheels running on the track; a sprocket-wheel connected with the main wheel of the truck; a harvester-frame supported on the said truck being journaled at one end and adjustably supported at the other; a cross-shaft jour-

naled on the said harvester-frame; a sprocket-wheel on the shaft connected by a sprocket-chain with the sprocket-wheel on the main wheel of the truck; a shaft longitudinally 5 journaled on the harvester-frame and geared to the aforesaid shaft; a crank-disk on the forward end of the longitudinal shaft; conveying and elevating chains upon the harvester carried by sprocket-wheels upon suitable shafts; and a sprocket-wheel and chain connection between the aforesaid longitudinal shaft and one of the latter, substantially as and for the purpose specified.

4. In a harvester-binder, and in combination with the elevator and needle thereof, a series of rods passing through holes at or near the apex between the elevator and binder-deck and extending above said apex, and means for automatically extending the said 15 rods simultaneously with the motion of the needle, substantially as and for the purpose specified.

5. In a harvester-binder, and in combination with the elevator and needle thereof, a series of rods passing through holes at or near the apex between the elevator and binder-deck, and means for automatically extending the said rods simultaneously with the motion of the needle; an apron supported above the 20 elevator and having its upper end turned outwardly and slotted; fingers connected to a suitably-journaled shaft and extending through the said slots normally close to the elevator, and means for swinging the said fingers backward simultaneously with the movement of the aforesaid rods, substantially as and for the purpose specified.

6. In a harvester-binder, and in combination with the elevator and needle thereof, a series of rods movably mounted to engage through holes at or near the apex between the elevator and binder-deck, and means for automatically extending the said rods simultaneously with the motion of the needle; a vertically-divided apron supported above the elevator and having its upper end turned outwardly and slotted; fingers connected to a suitably-journaled shaft and extending through the said slots normally close to the 45 elevator, and means for swinging the said fin-

gers backward simultaneously with the movement of the aforesaid rods, substantially as and for the purpose specified.

7. In a harvester-binder, an elevator provided with elevating-chains running over sprocket-wheels upon suitably-journaled shafts; means for driving the said shafts; a vertically-divided slotted spring-apron supported close to the said elevator; a shaft journaled above the bottom of the apron; a series of disks connected to the said shaft and provided with fingers which fingers only are adapted to extend through slots in the apron; and a gear connection between the said shaft and an elevator-chain-driving shaft, substantially as and for the purpose specified.

8. In a harvester-binder, a combined rim having a track formed on its inner periphery, combined with a truck running on said track, and a harvester-frame hinged at one end of the truck-frame and adjustably supported upon it at the other, and means for tilting the truck-frame, substantially as and for the purpose specified.

9. In a harvester-binder, the combination with the elevator and needle thereof, of a series of rods movable through holes at or near the apex between the elevator and binder-deck, means for automatically extending said rods simultaneously with the motion of the needle, a slotted apron, fingers extended through the slots of the apron and means for simultaneously actuating said fingers and rods, substantially as and for the purpose specified.

10. In a harvester-binder, the combination with the elevator and needle thereof, of a series of rods movable through holes at or near the apex between the elevator and binder-deck, means for automatically simultaneously actuating the needle and rods, and fingers extended above said apex, and means for moving said fingers simultaneously with the movement of said rods, substantially as and for the purpose specified.

Calgary, September 7, 1900.

JOHN ALEXANDER COWAN.
